UNITED STATES PATENT OFFICE.

GEORGE F. MANSFIELD, OF SCRANTON, MISSISSIPPI.

STOCKING-SUPPORTING MEANS.

No. 849,253.

Specification of Letters Patent.

Patented April 2, 1907.

Application filed December 29, 1906. Serial No. 350,034.

To all whom it may concern:

Be it known that I, GEORGE F. MANSFIELD, a citizen of the United States, residing at Scranton, in the county of Jackson and State 5 of Mississippi, have invented a new and useful Stocking-Supporting Means, of which the following is a specification.

This invention relates more particularly to means for supporting socks or stockings from 10 short or knee drawers. It is a well-known fact that it is the usual custom to employ in connection with this type of drawers garters that encircle the legs; but these are uncomfortable, and tend to stop the circulation of 15 blood.

The object of the present invention, therefore, is to provide simple means of a novel nature whereby the socks or stockings are supported directly from the drawers, said means 20 being readily adjustable, so that supporters may be properly fitted to the wearer.

The preferred form of construction is illustrated in the accompanying drawings, where- 25 in—

Figure 1 is a detail perspective view showing the supporters in place. Fig. 2 is a detail sectional view through a portion of the supporter and showing the same on an enlarged scale. Fig. 3 is a face view of the 30 garter.

Similar reference-numerals designate corresponding parts in all the figures of the drawings.

In the embodiment illustrated the drawers 35 are shown at 4, and the socks to be supported are designated 5. The lower ends of the drawer-legs are provided with depending tabs 6, having buttonholes 7 therein. Each 40 of the garters comprises an elastic strap 8, the upper end of which is formed into a loop 9, secured by a buckle-plate 10. The outer wall 11 of the loop has an opening 12 therethrough. A button has a base 13, located 45 within the loop, and a shank 14, that projects through the opening 12 and is provided at its outer end with a head 15. The strap is also formed into a lower loop 16, in which is 50 located a sock or stocking engaging clamp 17. The lower terminal of the strap is interlocked in a buckle-plate 18, that is slidably mounted on an intermediate portion of the strap. It

will thus be apparent that the garter may be lengthened or shortened, as desired, by sliding the buckle-strap 18 on the fabric or webbing.

The use of the device will be clearly evident by reference to Figs. 1 and 2, wherein it will be noted that the button is engaged in the buttonhole 7 of the tab 6, and the clamp 17 is engaged with the sock or stocking in the usual manner. It will thus be seen that the 60 socks or stockings will be supported directly from the drawers, and there will be no binding action upon the legs of the wearer. Furthermore, the garters can be extended or shortened, as desired, so that they may be 65 properly fitted.

From the foregoing it is thought that the construction, operation, and many advantages of the herein-described invention will be apparent to those skilled in the art without further description, and it will be understood that various changes in the size, shape, proportion, and minor details of construction may be resorted to without departing from the spirit or sacrificing any of the advantages 75 of the invention.

Having thus fully described my invention, what I claim as new, and desire to secure by Letters Patent, is—

The combination with a drawers-leg having a tab provided with a buttonhole, of a strap having a loop formed at its upper end, one wall of such loop having an opening therethrough, a button having a base located within and inclosed by the loop, and a shank 80 extending through said opening in the wall and projecting from said loop, said shank detachably engaging in the buttonhole of the tab, means adjustably connecting the lower 85 terminal of the strap to an intermediate portion of the same, forming a lower adjustable loop, and a stocking-engaging device having 90 a portion engaged in the latter loop and adjustable therewith.

In testimony that I claim the foregoing as 95 my own I have hereto affixed my signature in the presence of two witnesses.

GEORGE F. MANSFIELD.
